UNITED STATES PATENT OFFICE.

FREDERICK W. COLE, OF NEWTON HIGHLANDS, MASSACHUSETTS.

FIRE-ALARM SIGNAL-BOX.

1,239,887.

Specification of Letters Patent. Patented Sept. 11, 1917.

Application filed April 19, 1916. Serial No. 92,292.

To all whom it may concern:

Be it known that I, FREDERICK W. COLE, a citizen of the United States, residing at Newton Highlands, in the county of Middlesex and State of Massachusetts, have invented an Improvement in Fire-Alarm Signal-Boxes, of which the following is a specification.

This invention relates to improvements in fire alarm signal-boxes and particularly to accessory means associated with the signal-transmitter designed for testing and for protecting the transmitter and other costly components of the box. In signal-boxes of this description, of the more advanced type, it is desirable to provide switching-means adapted to be operated by an inspector when the door is open, to electrically connect the circuit-wires at both sides of the transmitter, thereby to shunt the transmitter, to enable it to be tested without interrupting the signal-circuit, and also admit of its removal and replacement; also to electrically connect a ground branch circuit with the signal-circuit at either side of the signal-transmitter, which connection may be made when the signal-circuit is broken to enable the signal-transmitter to transmit its signal over a ground-circuit while the broken line is being repaired; also to provide protective-means commonly known as a lightning arrester, which is associated with the leading-in wires, thereby to protect the transmitter and other costly components of the box from injury in case a heavy current should pass over the signal-circuit.

Heretofore various means have been provided for accomplishing these results. Sometimes several independent switches arranged on an insulating base have been employed; sometimes switches involving the employment of a switch-plug have been employed; but these various means are open to certain objections, as for instance, one or more of the switches may be left in wrong positions by the inspector with the result that the box is cut out or otherwise prevented from transmitting its signal over the signal-circuit, or the switch-plug may be left in engaging position in the box, or the inspector may not have a switch-plug with him, or the switch-plug may be placed in a wrong engaging-position by an unskilled inspector.

55 The present invention has for its object the provision of a switching-device of a ro-

tary character adapted to be operated when the door is open, to make a multiplicity of electrical connections, to accomplish the several results above referred to, as, for instance, in one position it electrically connects the circuit-wires at both sides of the signal-transmitter, thereby to shunt the transmitter, for testing purposes or for the removal and replacement of the transmitter; and when in another position it electrically connects a ground branch circuit with the signal-circuit at one side of the signal-transmitter, and when in other positions it disengages the aforesaid electrical connections, these latter positions being termed the neutral positions of the switching-device.

The present invention also involves the provision of three switch terminals, two for the leading-in wires of the signal-circuit, and one for a ground branch circuit, and all of which are widely separated and equally spaced around a common center, and around which the movable switch device revolves, and heavily insulated holding buttons arranged in the spaces between the switch terminals; and also the provision of cylindrical carbon jacketed lightning arrester posts connected with the leading-in wires and the ground branch terminals. Said posts, by their construction and close association, serve as a protecting-means for the signal-transmitter in case a heavy current should pass over the signal-circuit, as those posts which are connected to the line are widely separated from each other, but lie very close to the grounded post which is arranged between them.

Figure 1 is a front elevation of a switching-means involving this invention, associated with a signal-box, which latter is shown in diagram.

Fig. 2 is a side view of the switching-means.

Fig. 3 is the bottom plan view of the switching-means.

Fig. 4 is a sectional view of the rotating switch-member.

Figs. 5, 6, and 7 are fragmentary views of the elements of the switching-device in different positions.

The signal-box illustrated in diagram, Fig. 1, comprises essentially a signal-wheel 1, a pivoted key-lever 2, a signal-key 3, composed of two resilient contact-members 110 adapted to be operated by the key-lever, a non-interference magnet 4, a shunt-circuit

closer 5 adapted to be operated by the key-lever, and also to be controlled by some component part of the box-mechanism, and a shunt circuit-closer 6 adapted to be controlled by the box door.

The component parts of the box thus briefly described are common in that type of fire-alarm signal-box known as the "Gamewell box." Electrically connected 10 with said component parts and with the signal-circuit is my newly invented switching-means and lightning-arrester. The rotary element of the switching-means consists of a rotatable spindle 10, extended 15 through an insulated base having a shoudered shank or knob 12 above said base for turning it, and a spring-acting disk-member 13 below said base tending to hold said spindle frictionally in any position it may 20 be set.

A two-armed member, here shown as a plate, the arms 15 and 16 of which are angularly related to each other, is fixed on the spindle, to be turned by it. The arms of 25 said plate occupy substantially the same plane, and they extend radially from the spindle but in different directions, being spaced approximately 120° apart.

Arranged in circular formation about said 30 spindle or concentric of the axis thereof are three stationarily supported contact-plates 20, 30, and 40, forming the stationary elements of the switching-means. The plate 20 has an attaching-portion 21 with laterally projecting ears 22, which are bent upward and inward, in circular formation, within the upper one of which a circuit wire 24 is soldered, which connects to the signal contacts of the transmitter, and said plate 35 is fixed to the base-plate by the binding-post 23, to which one of the leading-in wires of the signal-circuit is connected. The plate 30 has an attaching-portion 31 with laterally projecting ears 32, which are bent 40 upward and inward in circular formation, in the upper one of which a circuit wire 34 is soldered which leads to the non-interference magnet of the transmitter, and said plate is fixed to the base-plate by a binding-post 33, to which one of the leading-in wires 45 of the signal-circuit is connected. The lower ear 22 of plate 20 is connected by a conductor 25, with a carbon post 50, which is positioned in close proximity to a like carbon post 55, on ground plate 40. The lower ear 32 of the plate 30 is connected by a conductor 35, with the carbon post 51, which is positioned in close proximity to a like carbon post 54, mounted on ground plate 40. The 50 plates 20, 30, and 40 are equidistantly disposed, being spaced apart about 120° , corresponding to the spacing of the arms 15 and 16, of the rotatable two-armed member, and the spaces between said plates are of greater 55 width than that of the arms. Said plates

20, 30, and 40 occupy substantially the same plane, and enter the path of movement of the arms 15 and 16, sufficiently to engage said arms as they are moved over them. When the spindle 10 is turned into one of 70 its numerous positions, said arms 15 and 16 will engage plates 30 and 20, see Fig. 6, and thus electrically connect the circuit-wires at both sides of the signal-transmitter, shunting the transmitter, and admitting of its 75 operation without transmitting its signal over the signal-circuit, and also providing for its removal and replacement without opening the circuit. The plate 40 has an attaching-portion 41, and is secured to the 80 base-plate by a binding-post 52, and a leading-in wire from a ground branch circuit is connected with said binding-post.

When the spindle bearing the two-armed plate is turned into another of its numerous 85 positions, one of the arms thereof, as 16, will engage the plate 40, and the other arm, as 15, will engage the plate 30, see Fig. 7, thus electrically connecting the ground branch circuit with the signal-circuit at one side of 90 the signal-transmitter, and when said spindle is turned into still another of its numerous positions, said two-armed plate is turned, and one of its arms, as 16, will engage the plate 40, and the other arm, as 15, 95 will engage the plate 20, see Fig. 5, thus electrically connecting the ground branch circuit with the signal-circuit at the other side of the signal-transmitter.

The switching-means thus described has 100 provision for three separate circuit-closing positions as described for the accomplishment of the results above set forth, but it also has positions intermediate the aforesaid positions, in which intermediate positions the two-armed member disengages the stationary plates, and in Fig. 1, one of such intermediate positions is shown. It is designed and intended that the switching-means shall be normally disposed in one of 105 these intermediate or neutral positions, and arranged on the base-plate between the several positions adapted to be occupied by the rotatable switching-member, are several 110 studs which serve to assist in correctly locating the arms of the rotatable member with respect to the stationary-plates and also with respect to their neutral positions.

As a reminder to call attention to an 115 inspector, that the rotatable switch-member has been left in the position shown in Fig. 6, in which position the signal-transmitter is prevented from sending its signal over the signal-circuit, means are herein provided for preventing the closing of 120 the door, if said switch-member is left in such position, which, as here shown, consists in a blade 60, arranged on the inside of the door 70, which blade is adapted to enter a transverse slot 61, formed in the head of the 130

knob 12, on the spindle 10. Unless the knob is in such position as to register with the blade on the door, said blade will strike the head of the knob, and the door cannot be closed. Whenever the blade occupies a position in this slot, the rotatable switch-member is in one of its intermediate or neutral positions, as represented in Fig. 1, except as hereinafter set forth. When the rotatable switch-member is turned to coact with the switch-plates 20 and 40, see Fig. 5, or 30, and 40, see Fig. 7, thus to connect the ground branch circuit with the signal-circuit at one or the other side of the signal-transmitter, it is important that the rotatable switch-member shall remain in these respective positions when the door is closed, so that the box will be left connected with the ground branch circuit and in condition for sending its signal over the grounded circuit in case the signal-circuit is broken, and until such break is repaired. Therefore, the head of the knob 12 has another slot 65, which is adapted to receive the blade 60. Upon reference to Fig. 5, it will be observed that the slot 65 is in position to receive the blade 60, when the door is closed; but when the switch-member is moved into the position shown in Fig. 7, which is its other ground connected position, it will be observed that the slot 61 is again utilized to receive the lug 60, when the door is closed.

It is obvious that slight changes may be made in the structure of the switching-means here shown and described, and also of the protecting-means, without departing from the scope of my invention.

I claim:—

1. A signal-box having a signal-transmitter adapted for connection with an electric circuit, switching-means for electrically connecting the circuit-wires at each side of the transmitter to form a shunt, said switching-means consisting of a pair of spaced contact-members adapted for electrical connection with the circuit-wires at each side of the transmitter, a rotatable two-armed contact-member adapted for movement into and out of engagement with said contact-plates, the arms of said contact-member being spaced apart, and means arranged on the inside of the door coacting with said rotatable member to permit closing of the door when member is in disengaged position and to prevent closing of the door when in engaged position.

2. A signal-box having a signal-transmitter adapted for connection with an electric circuit, switching-means for electrically connecting the circuit-wires at each side of the transmitter to form a shunt, said switching-means consisting of a rotatable two-armed contact-plate, and a pair of stationary contact-plates arranged concentrically to the axis of rotation of the two-armed plate, said

stationary plates being connected with the circuit-wires at each side of the transmitter, and widely spaced apart, and the arms of said two-armed plate being spaced apart, and insulated studs arranged in the spaces adjacent the stationary contact plates for engagement with the arms of the rotatable contact plate, tending to maintain said arms in disengaged positions.

3. A signal-box having a signal-transmitter adapted for connection with an electric circuit, switching-means for electrically connecting the circuit-wires at each side of the transmitter to form a shunt, said means consisting of a rotatable two-armed contact-plate having a turning knob, a pair of stationary contact-plates having attaching-portions with binding-posts thereon for connection with the circuit-wires at each side of the transmitter, said stationary plates being arranged concentric to the axis of rotation of the two-armed plate, and spaced apart, and the arms of the two-armed plate being angularly related, and insulated studs arranged in the spaces adjacent the stationary contact plates for engagement with the arms of the rotatable contact plate, tending to maintain said arms in disengaged positions.

4. A signal-box having a signal-transmitter adapted for connection with an electric circuit, switching-means for electrically connecting the circuit-wires at each side of the transmitter to form a shunt, said means consisting of a pair of contact-members adapted for electrical connection with the circuit-wires at each side of the transmitter, and a rotatable two-armed member adapted for movement into and out of engagement with said contact-plates, a spindle bearing said two-armed member having a turning knob with a transverse slot, and an abutment arranged on the inside of the door adapted to enter said slot when the knob is in a predetermined position, thus permitting closing of the door, and when said knob is in another position to form an obstruction to prevent closing said door.

5. A signal-box having a signal-transmitter adapted for connection with an electric circuit, switching-means for electrically connecting the circuit-wires at each side of the transmitter to form a shunt, said means consisting of a rotatable two-armed contact-plate, a pair of widely separated stationary contact-plates adapted for connection with the circuit-wires at each side of the transmitter with which said two-armed plate coacts, a pair of carbon jacketed posts, and conductors connecting said jacketed posts with the stationary contact-plates, and a ground branch terminal connected to similar carbon jacketed posts arranged between and in close relation to the circuit wire terminals.

6. A signal-box having a signal-transmit-

ter adapted for connection with a signal-circuit, switching-means for electrically connecting the circuit-wires at each side of the transmitter to form a shunt, said means comprising a movable member and a pair of stationary contact-plates, spaced apart and adapted for connection with the circuit-wires at each side of the transmitter with which said movable member is adapted to 10 coact, a pair of carbon jacketed posts for the leading-in wires of the signal-circuit, and conductors connecting said binding-posts to the stationary contact-plates.

7. A signal-box having a signal-transmitter adapted for connection with a signal-circuit, switching-means for electrically connecting the circuit-wires at each side of the transmitter to form a shunt, said means comprising a movable member and a pair of 15 stationary contact-plates spaced apart and adapted for connection with the circuit-wires at each side of the transmitter with which said movable member is adapted to coact, a pair of carbon jacketed posts for the leading-in wires of the signal-circuit, conductors connecting said jacketed posts to the stationary contact plates, and a ground branch terminal carbon jacketed post arranged between said binding-posts and in 20 close proximity thereto:

8. A signal-box having a signal-transmitter adapted for connection with a signal-circuit, switching-means for electrically connecting the circuit-wires at each side of the transmitter to form a shunt, said means comprising a movable member and a pair of 25 stationary contact-plates spaced apart and adapted for connection with the circuit-wires at each side of the transmitter with which said movable member is adapted to coact, a pair of carbon jacketed posts for the leading-in wires of the signal-circuit, conductors connecting said binding-posts to the stationary contact-plates, and a stationary 30 plate with a binding-post thereon adapted to be connected with a ground branch circuit and carbon jacketed posts arranged thereon and in close proximity to and between the aforesaid posts connected to the 35 terminals for the circuit wires.

9. A signal-box having a signal-transmitter adapted for connection with a signal-circuit, switching-means for electrically connecting the circuit-wires at each side of the transmitter to form a shunt, and for connecting a ground branch circuit with either of said circuit-wires, said switching-means comprising a rotatable bridging-member, a 40 pair of stationary contact-plates electrically connected with the circuit-wires at each side of the transmitter, a stationary contact-plate adapted for electrical connection with a ground branch circuit, said stationary contact-plates being arranged about the axis of 45 rotation of the bridging member and spaced

equally apart, said bridging member being adapted for coaction with any two adjacent contact-plates only.

10. A signal-box having a signal-transmitter adapted for connection with an electric circuit, switching-means for electrically connecting the circuit-wires at each side of the transmitter to form a shunt, and for connecting a ground branch circuit with either of said circuit-wires, said switching-means comprising a rotatable two-armed contact-member, a pair of stationary contact-members electrically connected with the circuit-wires at each side of the transmitter, and a stationary contact-member adapted for connection with a ground branch circuit, said stationary contact-members being arranged concentrically to the axis of rotation of the two-armed member, and equidistantly separated, and the arms of said two-armed member being angularly related to each other.

11. A signal-box having a signal-transmitter adapted for connection with an electric circuit, switching-means for electrically connecting the circuit-wires at each side of the transmitter to form a shunt and for connecting a ground branch circuit with either of said circuit-wires, said switching-means comprising a rotatable two-armed contact-plate, a pair of stationary contact-plates electrically connected with the circuit-wires at each side of the transmitter, and a stationary contact-plate adapted for connection with a ground branch circuit, said stationary contact-plates being arranged concentrically to the axis of rotation of the two-armed plate and equidistantly separated, the spaces between said stationary plates being wider than the arms of the two-armed 100 plate.

12. A signal-box having a signal-transmitter adapted for connection with an electric circuit, switching-means for electrically connecting the circuit-wires at each side of the transmitter to form a shunt and for connecting a ground branch circuit with either of said circuit-wires, said switching-means comprising a rotatable two-armed contact-plate, a pair of stationary contact-plates 110 electrically connected with the circuit-wires at each side of the transmitter, and a stationary contact-plate adapted for connection with a ground branch circuit, said stationary contact-plates being arranged concentrically to the axis of rotation of the two-armed plate and equidistantly separated, the spaces between said stationary plates being wider than the arms of the two-armed plate, and insulated means arranged 115 in the spaces between the stationary contact plates for engagement with the arms of the rotatable contact plate, tending to maintain said arms in disengaged position.

13. A signal-box having a signal-trans-

- mitter adapted for connection with a signal-circuit, switching-means for electrically connecting the circuit-wires at each side of the transmitter to form a shunt, and for 5 connecting a ground branch circuit with either of said circuit-wires, said switching-means comprising a rotatable bridging-member, a pair of stationary contact-plates electrically connected with the circuit-wires 10 at each side of the transmitter, a stationary contact-plate adapted for electrical connection with the ground branch circuit, said stationary contact-plates being arranged about the axis of rotation of the bridging-member and spaced apart, said bridging-member being adapted for coaction with any two adjacent contact-plates, and having a turning member with slots, and an abutment on the inside of the door adapted to 15 enter either of said slots and thereby permit closing of the door when the turning member is in predetermined positions, and in other positions, to form an obstruction to prevent closing of the door. 20 14. A signal-box having a signal-transmitter adapted for connection with a signal-circuit, switching-means for electrically connecting the circuit-wires at each side of the transmitter to form a shunt, and for 25 connecting a ground branch circuit with either of said circuit-wires, said switching-means comprising a rotatable bridging-member, a pair of stationary contact-plates electrically connected with the circuit-wires 30 at each side of the transmitter, a stationary contact-plate adapted for electrical connection with the ground branch circuit, said stationary contact-plates being arranged about the axis of rotation of the bridging-member and spaced apart, said bridging-member being adapted for coaction with any two adjacent contact-plates, widely 35 separated binding-posts to which the leading-in wires of the signal-circuit are connected, carbon jacketed posts electrically connected with said stationary plates and to which the circuit-wires are connected, a binding-post on the stationary plate to which the leading-in wire connected with the ground branch circuit is connected, and a carbon jacketed post on said last-named plate arranged in the spaces between the aforesaid jacketed posts and in close proximity thereto. 40
15. A signal-box having a signal-transmitter adapted for connection with a signal-circuit, switching-means for electrically connecting the circuit-wires at each side of the transmitter to form a shunt, and for the inside of the door coacting with said turning-member to permit closing of the door when said turning-member is in certain positions to prevent closing of the door when in other positions. 45
16. A signal-box having a signal-transmitter adapted for connection with a signal-circuit, switching-means for electrically connecting the circuit-wires at each side of the transmitter to form a shunt, and for connecting a ground branch circuit with either of said circuit-wires, said switching-means comprising a rotatable bridging-member, a pair of stationary contact-plates electrically connected with the circuit-wires 50 at each side of the transmitter, a stationary contact-plate adapted for electrical connection with the ground branch circuit, said stationary contact-plates being arranged about the axis of rotation of the bridging-member and spaced apart, said bridging-member being adapted for coaction with any two adjacent contact-plates, widely 55 separated binding-posts to which the leading-in wires of the signal-circuit are connected, carbon jacketed posts electrically connected with said stationary plates and to which the circuit-wires are connected, a binding-post on the stationary plate to which the leading-in wire connected with the ground branch circuit is connected, and a carbon jacketed post on said last-named plate arranged in the spaces between the aforesaid jacketed posts and in close proximity thereto. 60
17. A signal-box having a signal-transmitter adapted for connection with a signal-circuit, switching-means for electrically connecting the circuit-wires at each side of the transmitter to form a shunt, and for connecting a ground branch circuit with either of said circuit-wires, said switching-means comprising a rotatable bridging-member, a pair of stationary contact-plates electrically connected with the circuit-wires 65 at each side of the transmitter, a stationary contact-plate adapted for electrical connection with the ground branch circuit, said stationary contact-plates being arranged about the axis of rotation of the bridging-member and spaced apart, said bridging-member being adapted for coaction with any two adjacent contact-plates, widely 70 separated binding-posts to which the leading-in wires of the signal-circuit are connected, carbon jacketed posts electrically connected with said stationary plates and to which the circuit-wires are connected, a binding-post on the stationary plate to which the leading-in wire connected with the ground branch circuit is connected, and a carbon jacketed post on said last-named plate arranged in the spaces between the aforesaid jacketed posts and in close proximity thereto. 75

In testimony whereof, I have signed my name to this specification, in the presence of two subscribing witnesses.
